(57) **CLAIM**

The ornamental design for a electrical box with movable access panel, as shown and described.

DESCRIPTION

FIG. 1 is a perspective view of the electrical box with movable access panel, shown in a first position.

FIG. 2 is a top plan view of the electrical box with movable access panel.

FIG. 3 is a bottom plan view thereof.

FIG. 4 is a front elevational view thereof.

FIG. 5 is a rear elevational view thereof.

FIG. 6 is a left side elevational view thereof.

FIG. 7 is a right side elevational view thereof.

FIG. 8 is a perspective view of the electrical box with movable access panel, in an alternate position.

FIG. 9 is a top plan view thereof.

FIG. 10 is a bottom plan view thereof.

FIG. 11 is a front elevational view thereof.

FIG. 12 is a rear elevational view thereof.

FIG. 13 is a left side elevational view thereof; and,

FIG. 14 is a right side elevational view thereof.

The broken lines in the drawings are for the purpose of illustrating portions of the electrical box with movable access panel that form no part of the claimed design.

1 Claim, 9 Drawing Sheets
